CHARLES F. KETTERING, OF DAYTON, OHIO, ASSIGNOR, BY MESNE ASSIGNMENTS, TO
GENERAL MOTORS RESEARCH CORPORATION, OF DAYTON, OHIO, A CORPORATION
OF DELAWARE.

CONDENSER.

Application filed December 20, 1920. Serial No. 431,866.

To all whom it may concern:

Be it known that I, CHARLES F. KETTERING, a citizen of the United States of America, residing at Dayton, county of Montgomery, and State of Ohio, have invented 5 certain new and useful Improvements in Condensers, of which the following is a full, clear, and exact description.

The present invention relates to condensers, and in the preferred form of embodiment, which has been chosen for the purpose of description and illustration, relates particularly to condensers for refrigeration systems.

15 In refrigeration systems of the so-called domestic type, it has heretofore been usual to utilize condensing chambers over the surface of which water was allowed to flow and in those systems wherein air condensers were 20 used, it has been found necessary, in order to get sufficient condensing surface, to form such condensers from a very long pipe of small diameter wound into rather large coils.

25 The objection to such forms of condensers is that, in the case of the water cooled type, the water supply is not always reliable and when such supply fails, the condensing action is practically nil. In the case of the ordinary type of air cooled condenser, the 30 large coils considered necessary to accomplish the condensing action, have occupied considerable space and are not particularly efficient.

35 Among the objects of the present invention, therefore, is a condenser which is air cooled, which is very efficient, and which for a given size of refrigeration system, shall be relatively small.

40 Further objects and advantages of the present invention will be apparent, reference being had to the accompanying drawing, wherein a preferred embodiment of the invention is clearly shown.

45 In the drawings:

Fig. 1 is a longitudinal section of a condenser made in accordance with the present invention, the section being taken on the line 1-1 of Fig. 2.

Fig. 2 is a plan view of the condenser shown in Fig. 1.

Fig. 3 is a diagrammatic illustration with the condenser relatively greatly enlarged, showing a refrigeration system using this form of condenser.

Figs. 4 and 5 are detail perspective views showing the arrangement of the external and the internal cooling elements respectively.

In Fig. 1 the condenser is indicated as being formed of an annular chamber 10 furnished with a suitable inlet 11 and outlet 12 carrying, upon both the inner and outer surfaces of the annulus, cooling elements indicated at 13 and 15, respectively. Surrounding the whole is a casing or draft tube 14 of suitable material in order that the cooling air may be confined to the surfaces of the cooling elements 15 and compelled to flow over said cooling elements rather than be dissipated and thus be ineffective. This 70 casing when made of heat conducting material also furnishes additional surface for heat dissipation.

These cooling elements are preferably made of thin sheet copper and are attached 75 to the walls of chamber 10 which may be of iron or steel, or some other suitable metal, even copper, and in effective thermal contact therewith. The cooling elements or fins are formed from sheet metal which is bent to 80 produce undulations or corrugations having flat sides and substantially right angled bends, though it will be apparent that the cooling elements may be of any desired shape or proportions. Referring to Figs. 4 and 5 85 which show the position of the cooling elements when applied with one side in contact with the outer or the inner surfaces of the annular chamber 10, it will be observed that the transverse flat surfaces of the corrugated strip dispose themselves radially with respect to the annular member, as is also shown in Fig. 2. The attachment of the cooling members to the chamber 10 is 90 preferably accomplished by a suitable brazing operation such as is described and 95

claimed in application, Serial No. 392,646, filed June 29, 1920, but in some cases soldering has been found to give good results.

A casing or draft tube 14 surrounds the annular chamber 10 in contact with the cooling elements 15 on the outer surface or side thereof, and cooperates therewith to provide longitudinally extending tubes, as is best shown in Fig. 2. In the embodiment of the invention illustrated the cooling elements 13 on the inner surface of the annular chamber 10 are arranged with their adjacent corrugations at one side in contact with one another thereby providing a central circular opening or tube surrounded by a series of tubes of alternately triangular and rectangular cross sections, as best shown in Figs. 2 and 5. It may thus be said that the opening through the annular chamber is filled with tubes, though it will be understood that the shape and proportions of the corrugations may be varied as desired to provide a larger or smaller number of tubes without departing from the spirit and scope of the invention.

In Fig. 3 there is represented a refrigeration system using the condenser described. In this figure the expansion chamber is represented conventionally at "E," the compressor at "P," the condenser at "C" and a suitable fan or blower for supplying air to the condenser is indicated at "B."

The condenser is herein shown as directly connected with the blower thereby eliminating all unnecessary resistance losses incident to the use of pipe connections between the blower and the condenser. The condenser is mounted on the blower housing and preferably in a vertical position thereon above the blower whereby the heated air is discharged upwardly.

From the above description it will be apparent that there has been provided a condenser apparatus particularly suitable for use in small refrigerators for household use wherein the qualities of simplicity and compactness without loss of efficiency are of paramount importance.

While the form of mechanism herein shown and described constitutes a preferred embodiment of one form of the present invention, it is to be understood that other forms might be adopted, and various changes and alterations made in the shape, size, and proportion of the elements therein without departing from the spirit and scope of the invention.

What I claim is as follows:

1. A condenser of the class described comprising a blower casing; an inner cylindrical condensing chamber and an outer cylindrical casing surrounding said chamber and spaced apart therefrom, both said elements being supported by and located above said blower casing; and a continuous strip of metal ar-

ranged within the space between said chamber and casing and which strip is bent to provide cooling portions or elements spaced apart from one another and extending across the space aforesaid, and attaching portions intermediate successive cooling elements; alternate ones of said attaching elements being in contact with the exterior surface of said condensing chamber, and with the interior surface of said outer casing.

2. In a condenser of the class described, an inner condensing chamber cylindrical in form and an outer cylindrical casing surrounding said chamber and spaced apart therefrom, and a continuous strip of metal arranged within the space between said members and bent to provide cooling portions or elements spaced apart from one another and extending across the space aforesaid, and attaching portions intermediate successive cooling elements; alternate ones of said attaching elements being in intimate contact with the exterior surface of said condensing chamber, and in contact also with the interior surface of said outer casing; and means for forcing air through the passages between said cooling elements.

3. A condenser of the class described comprising an inner condensing chamber cylindrical in form and an outer casing surrounding said chamber and spaced apart therefrom, and a continuous strip of metal arranged within the space between said members and bent to provide cooling portions or elements spaced apart from one another and extending across the space aforesaid, and flat attaching portions intermediate successive cooling elements; alternate ones of said flat attaching elements being in contact with the exterior surface of said condensing chamber, and with the interior surface of said outer casing, to thereby provide areas of contact of considerable extent between said attaching strip and said condensing chamber and outer casing.

4. A condenser of the class described comprising an inner condensing chamber and an outer casing surrounding said chamber and spaced apart therefrom, and a continuous strip of metal arranged within the space between said members and bent to provide cooling portions or elements spaced apart from one another and extending across the space aforesaid, and attaching portions intermediate successive cooling elements; alternate ones of said attaching elements being in contact with the exterior surface of said condensing chamber, and with the interior surface of said outer casing.

5. A condenser of the class described comprising an inner annular cylindrical condensing chamber, and an outer cylindrical casing surrounding said chamber and spaced apart therefrom; and a continuous strip of

metal arranged within the space between said members and bent to provide cooling portions or elements spaced apart from one another and extending across the space ¹⁰ aforesaid, and attaching portions intermediate successive cooling elements; alternate ones of said attaching elements being in contact with the exterior surface of said con-

densing chamber, and with the interior surface of said outer casing.

In testimony whereof I hereto affix my signature.

CHARLES F. KETTERING.
